Primary Examiner — Marcus Jackson(74) *Attorney, Agent, or Firm* — Kilpatrick Townsend & Stockton LLP**(57) CLAIM**

The ornamental design for electrode-less lamp assembly, as shown and described.

DESCRIPTION

FIG. 1 is a perspective view of an electrode-less lamp assembly showing our new design;

FIG. 2 is a side view thereof;

FIG. 3 is a top view thereof; and,

FIG. 4 is a bottom view thereof.

The broken lines shown represent unclaimed subject matter and form no part of the claimed design.
